BRAKE OPERATING DEVICE FOR FLAT CARS

Filed March 29, 1927

FIG. 1

A technical drawing of a circular component. The outer boundary is marked with the number 24 at the top and 22 at the bottom. Along the left side, the numbers 16 and 18 are marked, with 16 above 18. Along the right side, the numbers 23 and 18 are marked, with 23 above 18. The central feature is a rectangular cutout labeled 25. The entire drawing is enclosed in a dashed circle.

UNITED STATES PATENT OFFICE.

WILLIAM D. BREWSTER, OF SYRACUSE, NEW YORK, ASSIGNOR TO NATIONAL BRAKE COMPANY INC., OF BUFFALO, NEW YORK, A CORPORATION OF NEW YORK.

BRAKE-OPERATING DEVICE FOR FLAT CARS.

Application filed March 29, 1927. Serial No. 179,278.

This invention relates to a brake-operating device for flat cars in which the winding drum for the brake-operating cable together with suitable gears are mounted within and upon a supporting frame which is secured to the underside of the frame work for the platform of the car and is provided with journal bearings for receiving and supporting an upright tubular shaft in which is mounted an upright brake staff having spline connections with the interior of the tubular shaft for rotating said shaft and permitting the staff to be adjusted endwise to different heights relatively to the upper surface of the platform of the car, the shaft serving to transmit rotary motion to the gears and winding drum for the cable.

The main object is to provide simple and efficient means whereby the brake staff may be easily and quickly adjusted vertically to its extreme up-position or to an extreme down-position so that its upper end will lie close to the upper surface of the platform of the car so that it may be operated at different levels for transmitting a rotary motion to the winding drum for the cable as may be required under different circumstances or, if necessary, the brake staff may be dropped to its extreme lower position to permit freight carried by the platform of the car to extend over the upper end of the staff.

One of the specific objects is to provide means whereby, when the brake staff is adjusted endwise to one position, the spline connections will be disengaged thus permitting angular adjustment of the brake staff relatively to the tubular shaft for re-engagement with a suitable stop or rest by slight endwise adjustment to another position for holding said staff in the last-named position.

Another object is to provide the frame with a displaceable journal-bearing for the tubular shaft to enable said shaft with the pinion thereon to be placed in operative position on the frame.

Other objects and uses relating to specific parts of the device will be brought out in the following description.

In the drawings:

Figure 1 is a top plan, partly in section, of a brake-operating device embodying the various features of my invention.

Figure 2 is a vertical sectional view taken in the plane of line 2—2, Figure 1, except

that a portion of the tubular shaft and brake staff are broken away.

Figures 3 and 4 are enlarged transverse sectional views taken respectively in the planes of lines 3—3 and 4—4, Figure 2.

Figure 5 is an enlarged detail sectional view taken on line 5—5, Figure 2.

Figure 6 is an enlarged transverse sectional view of the detached brake staff.

Figure 7 is an enlarged transverse sectional view of the detached tubular shaft.

As illustrated, this device comprises a hollow or open frame —1— having a vertical bearing shaft —2— near the center thereof and lower and upper bearings —3— and —4— some distance to one side of the bearing shaft —2—.

This frame is preferably made of cast metal and adapted to be bolted or otherwise secured to the underside of the frame work of the platform as —A— of the car shown by dotted lines in Figure 2 and preferably comprises a substantially horizontal top bar —5— and a lower bar —6— integrally united to the top bar —5—.

The lower and upper ends of the shaft —2— are secured in vertically aligned openings in the top and bottom bars —5— and —6— and if desired may be held against turning by a cross pin —7— extending through registering apertures in the lower end of the shaft —2— and bottom bar —6—.

The journal bearings —3— and —4— are arranged in vertically spaced relation, the bearing —4— being displaceable from the top portion of the frame —1—, but is normally held in operative position by a locking pin or key —8—.

An eccentric drum —9— is journaled upon the upright shaft —2— between the top and bottom bars —5— and —6— of the frame —1— and is held against axial movement by the engagement of its opposite ends with said base.

A cable consisting, in this instance, of a chain —10— is connected at one end to the periphery of the eccentric portion of the drum —9— to be wound thereon as the drum is rotated in one direction, the other end of the cable being operatively connected in any suitable manner to the car-brake, not shown.

The drum —9— is provided with a relatively large gear —11— meshing with a pinion —12— which is normally interposed

between the lower and upper bearings —3— and —4— and is held against endwise movement by engagement with the inner ends of said bearings.

5 This pinion is rigidly secured to and may be formed integral with an upright tubular shaft —13— which extends some distance above and below the upper and lower ends of the pinion and is journaled in the bearings —3— and —4— for rotating the pinion —12—, gear —11— and drum —9—.

When placing the tubular shaft —13— with the pinion —12— thereon in operative position the bearing section —4— of the top bar 15 —5— is removed after removing the locking pin —8— whereupon the lower end of the tubular shaft is inserted in the lower bearing —3— so that the lower end of the pinion may rest upon the upper end of said bar 20 after which the bearing member —4— is replaced in operative position over the upper end of the tubular shaft and locked in position by the key or pin —8— to assist the lower bearing in holding the tubular shaft in an 25 upright position.

A brake staff —14— is slidable endwise of and within the tubular shaft —13— and is provided at its upper end with a hand wheel —15— by which it may be rotated.

30 Rotary motion is transmitted from the staff —14— to the tubular shaft —13— through the medium of spline connections between the staff and interior of the shaft which also permits axial adjustment of the staff to different levels as may be required for convenience of operation or for convenience of loading and unloading freight upon and from the platform of the car.

40 Suitable means is also provided for permitting angular adjustment of the staff relatively to the tubular shaft when adjusted endwise to a certain position and thereby to cooperate with means for holding the staff in an elevated position by a limited endwise adjustment to another position, said staff and shaft being provided with cooperative means for limiting the angular adjustment of the staff when adjusted endwise to its turning position relatively to the shaft.

45 I have preferably provided the staff and shaft with axially spaced spline connections and with intervening reduced portions and enlarged interior portions so that when the staff is adjusted to a certain position both spline connections will be disengaged and the reduced portion of the staff registered with one of the splines in the upper end of the shaft to permit said angular movement.

That is, the tubular shaft —13— is provided with internal lengthwise ways or grooves —16— preferably of rectangular cross section and arranged at the four corners of a square extending upwardly from the lower end thereof and terminating a relatively short distance from the upper end

thereby forming what may be termed a rectangular or square opening or spline-way while the upper end of the same shaft is provided with a central rectangular opening —17— in axially spaced relation to and of substantially the same cross sectional form as the spline-way —16— to form another spline-way in axially spaced relation to the first-named spline-way, the intervening portion of the interior between the spline-ways 75 being enlarged at —18— and of greater radius than the radius through any one of the four corners of the first-named spline-way —16— for a purpose presently described.

The major portion of the staff —14— from the wheel —15— downwardly is rectangular or square in cross section corresponding approximately to the cross sectional form of the spline-ways —16— and —17— along which it is adapted to move endwise for transmitting rotary motion from the staff to the tubular shaft and constituting what may be termed a spline or key —19—.

The lower end of the staff —14— is provided with a substantially rectangular head 90 —20— which is mainly square and of substantially the same radius through its corners as the corresponding radii of the spline-way —16— along which it is adapted to move endwise to assist in transmitting rotary motion 95 from the staff to the tubular shaft and constituting what may be termed another spline.

These splines —19— and —20— are arranged in axially spaced relation and the intervening portion —21— thereof is reduced and preferably cylindrical or of less cross sectional area than that of spline-ways —16— and —17—.

The length of the spline head —20— is somewhat less than the axial length of the enlarged opening —18— while the length of the cylindrical portion —21— is somewhat greater than the length of the spline-way —17— so that when the spline —14— is adjusted upwardly to register the cylindrical portion —21— with the spline-way —17— the spline head —20— will be brought into registration with the enlarged opening —18— thus permitting angular adjustment of the staff relatively to the tubular shaft for a purpose 110 presently described.

On the other hand, when the staff —19— is adjusted to bring the cylindrical portion —21— below the spline-way —17— the square portions —19— and —20— will be engaged with their respective spline-ways —17— and —16— for transmitting rotary motion to the tubular shaft.

Suitable means is provided for limiting the angular movement of the staff —14— relatively to the tubular shaft —13— through an arc of approximately ninety degrees when the spline head —20— is registered with the enlarged opening —18— and for this purpose two diametrically opposite portions of the 125 130

inner walls of said enlargement near two of the diagonally opposite corners of the spline ways —16— and —17— are extended inwardly along diagonally opposite sides of said corners to form stop shoulders or abutments —22— while the adjacent sides of the spline ways —16— form additional stop shoulders adapted to be engaged by the splines —19— and —20— when the staff is adjusted rotarily 10 in one direction as shown in Figure 3.

The interior of the tubular shaft —13— is also provided with diametrically opposite grooves or key ways —23— extending from its lower end to the enlargement —18—, said 15 shaft being also provided with diametrically opposite but relatively short lengthwise grooves —24— extending from the enlargement —18— downwardly a distance corresponding approximately to the length of the 20 spline head —20— and constituting additional key-ways.

The grooves —24— are disposed substantially midway between the grooves —23— and all of the grooves —23— and —24— are substantially semi-circular in cross section.

The bottoms of the grooves —24— constitute seats or abutments —25— upon which the lower end of the staff —19— is adapted to rest when adjusted to the position shown 30 in Figure 2.

The spline head —20— on the lower end of the staff —19— is provided with keys or ribs —26— on two of its diametrically opposite sides and of substantially the same cross sectional form as the grooves —23— and —24— in which they are adapted to engage when the staff —19— is adjusted axially and rotarily to different positions.

For example, when it is desired to drop 40 the staff from its uppermost position as shown in Figure 2 to its lowermost position it will first be elevated to register the cylindrical portion —21— with the spline-way —17— and its spline head —20— with the enlargement —18— whereupon the staff may be adjusted angularly to bring its keys or ribs —26— into registration with the grooves —23— at which time further rotation in the same direction will be limited by the engagement 50 of the corners of the head —20— with corresponding sides of the spline-ways —16— whereupon the staff may be lowered to its extreme down-position or until the hand wheel —15— is nearly at the level of the platform 55 A of the car.

On the other hand, when it is desired to use the staff in its extreme elevated position it would be drawn upwardly until the cylindrical portion —21— is registered with the spline-way —17— at which time the head —20— will be registered with the enlargement —18— thus permitting the angular adjustment of the staff until limited by the engagement of the ribs —26— with the shoulders —22— and in registration with the rela-

tively short grooves —24— thus permitting the staff to be slightly lowered until limited by the engagement of the lower ends of the ribs —26— with the seats or abutments —25—.

It will be seen from the foregoing description that when the brake staff —19— is seated on the abutments —25— and also when it is dropped to its extreme down-position it will have axially spaced spline connections 70 with the tubular shaft —13— above and below the enlargement —18— for transmitting rotary motion therefrom to the shaft —13— and thence through the pinion —12— and gear —11— to the wheel drum —9— for the 80 cable —10— for tightening and releasing the brake.

Owing to the fact that the ribs —26— are formed upon the brake staff —14— it becomes necessary to insert the brake staff from the 85 bottom upwardly through the tubular shaft —13— before the hand wheel —15— is attached to the upper end of the staff and after the upper end of the staff passes through and above the upper end of the shaft, the hand 90 wheel —15— is secured thereto as shown in Figure 2.

It will be observed that when the brake staff is supported in its uppermost position in the grooves —24— as shown in Figure 3 it 95 may be lowered to its extreme low position or until the hand wheel —15— rests upon the upper end face of the shaft —13— by first lifting the staff to register its cylindrical part —21— with the spline way —17— which will also register the head —20— with the enlargements —21— whereupon the staff may be turned counterclockwise to bring its ribs —26— into registration with the grooves —23—, the staff being then free to drop by its 100 own weight to its lowermost position.

The operation of the invention will now be readily understood and while the construction shown and described is particularly simple and efficient it is evident that various 110 changes may be made in the detail construction without departing from the spirit of the invention.

What I claim is:

1. In a brake-operating device for flat cars, 115 a frame, an upright tubular shaft rotatably mounted on the frame and provided with a reduced angular opening in its upper end, a drop-staff having a portion thereof of similar angular cross-section slidable endwise in said opening to cause the staff and shaft to rotate together, said staff having a portion thereof of less size than the opening to allow it to turn therein when the staff is adjusted axially to register its reduced portion with the angular opening.

2. In a brake-operating device for flat cars, 125 a frame, an upright tubular shaft rotatably mounted on the frame, a drop staff slidable endwise of and within the tubular shaft, said 130

shaft and staff having axially spaced spline-connections one with the other to cause them to rotate together, the interior of the portion of the shaft and exterior of the portion of staff between the spline-connections being respectively enlarged and reduced to permit relative angular movement of those parts when the staff is adjusted endwise to a certain position, and means for limiting said relative angular movement.

3. A brake-operating device for flat cars as in claim 2 in which means is provided for holding the staff against downward movement when adjusted endwise to another position when said relative angular movement reaches its limit.

4. In a brake-operating device for flat cars, a frame, an upright rotary tubular shaft journaled in the frame, means for holding the shaft against endwise movement relatively to said frame, a brake staff slideable endwise of and within the shaft, spline connections between portions of the staff and shaft to cause them to rotate together when the staff is adjusted endwise to a certain position, other portions of said shaft and staff being without spline connections for permitting angular movement of the staff relatively to the shaft when the staff is adjusted endwise to another position, cooperative stops on the shaft and staff for limiting said angular adjustment when the staff is in the last-named position, and cooperative means on the shaft and staff for holding the staff against downward movement when the spline connections are

engaged in one position of axial adjustment.

5. In a brake-operating device for flat cars, a frame, an upright tubular shaft rotatably mounted on the frame, and an operating staff having separate axially spaced spline connections with the interior of the shaft and a reduced portion between said separate spline connections whereby the axial adjustment of the staff to a certain position will disengage both spline connections and permit rotation of the staff relatively to the shaft.

6. In a brake-operating device for flat cars, a frame having vertically spaced journal-bearings, an upright tubular shaft journaled in said bearings, one of said bearings being displaceable to permit the placement of the shaft in the other bearing, a brake-staff slideable endwise of and within the shaft, spline connections between the shaft and staff to cause them to rotate together when the staff is adjusted endwise to a certain position, other portions of the shaft and staff being without spline connections for permitting angular adjustment of the staff relatively to the shaft when the staff is adjusted endwise to another position, cooperative stops on the shaft and staff for limiting said angular adjustment when the staff is in the last-named position, and means for holding the staff against downward movement when adjusted endwise to said last-named position following the limiting of its angular adjustment.

In witness whereof I have hereunto set my hand this 22nd day of March, 1927.

WILLIAM D. BREWSTER.
